No. 14,234,

Aug. 21. 1883

UNITED STATES PATENT OFFICE.

FRANK A. WOODHEAD, OF PHILADELPHIA, PENNSYLVANIA, ASSIGNOR TO HORATIO BARRACLOUGH, OF SAME PLACE.

DESIGN FOR A WOVEN SHAWL.

SPECIFICATION forming part of Design No. 14,234, dated August 21, 1883.

Application filed July 5, 1883. Term of patent 3½ years.

To all whom it may concern:

Be it known that I, FRANK A. WOODHEAD, a subject of the Queen of Great Britain, residing at Philadelphia, in the county of Philadelphia and State of Pennsylvania, have invented and produced a new and original Design for a Pattern to be Inwrought in a Shawl—such as is known to the trade as an "India Shawl"—in such colors or shades of materials as may be desired; and I do hereby declare that the photographic print accompanying this specification conveys to any one skilled in the art of weaving India shawls a clear understanding of the same, and is sufficient to enable such person to use my invention.

15

What I claim as my invention, and desire to secure by Letters Patent, is—

The design for an India shawl, as shown in the photographic print accompanying this specification.

FRANK A. WOODHEAD.
